UNITED STATES PATENT OFFICE.

JOHN M. WADDILL, OF REIDSVILLE, NORTH CAROLINA.

BOX.

SPECIFICATION forming part of Letters Patent No. 375,518, dated December 27, 1887.

Application filed October 27, 1887. Serial No. 253,537. (No model.)

To all whom it may concern:

Be it known that I, JOHN M. WADDILL, a citizen of the United States, residing at Reidsville, in the county of Rockingham and State 5 of North Carolina, have invented a new and useful Improvement in Boxes, of which the following is a specification.

This invention relates to boxes; and it consists in the peculiar construction, combination, and arrangement of parts, as will be hereinafter set forth, and particularly pointed out in the claims.

In the accompanying drawings, wherein similar letters of reference denote corresponding parts in all the views, Figure 1 is a plan view of the blank from which the box is made. Fig. 2 is a perspective view of the completed box. Fig. 3 is a detail view of the clip which is used to secure the parts of the box together.

Referring by letter to the drawings, Fig. 1 shows the blank from which the box of Fig. 2 is formed, and it comprises the folds *a b c d* and the flaps *g h k l* on the edges of the said folds, the dotted lines indicating the divisional 25 and folding lines, which may be scored to insure accurate bending. The flaps *g k* have the V-shaped notches cut in their outer edges, which form the tongues *g² g³* and *k² k³* on opposite sides of the said notches, respectively.

The tongues *g²* and *k²* are rounded at the ends and the tongues *g³ k³* are angular. It will be seen that the tongues *g² g³* and *k² k³* form forks at the outer ends of the flaps *g* and *k*. The flaps *l l* on the side edges of the fold *d* are 35 very narrow, and a similar narrow flap, *m*, is formed on the outer or front edge of the fold *d*. This flap *m* is provided at the ends with the ears *n n*.

The fold *b* comprises the bottom of the box, 40 the folds *a* and *c* comprise, respectively, the front and rear sides, and the fold *d* comprises the lid or cover of the box. To form the box, therefore, from the blank, as described, the folds *a* and *c* are bent up at right angles to the 45 bottom fold, *b*, and the flaps *h h* are folded up to fill the spaces between the ends of the folds *a c*, and thus form the ends of the box. The flaps *g* and *k* are now folded toward each other on the outside of the flaps *h h*, and the forks 50 on the ends of the said flaps are caused to interlace, so that the tongues *g²* and *k²* will be on the outside (or exposed to view) and the

tongues *g³* and *k³* will be on the inside, (or concealed.)

The ends of the rounded tongues *g² k²* are 55 fastened down to the sides of the box by the clips *O O*, the points *S S* of which are passed through the said tongues and the end flaps and bent or turned over on the inside. The ends of the tongues *g³ k³* are rounded to improve the appearance of the outside of the box, and also to avoid exposing angles or unfastened edges, which would be liable to be turned up in using the box. The tongues *g³* and *k³* are concealed, as before stated, and 65 therefore there is no necessity to round their ends.

By constructing the body of the box in the manner described there are three thicknesses of material at each end thereof, which will 70 prevent the ends from collapsing, and will also strengthen the front and rear sides, thereby rendering the entire box very rigid and substantial.

Having now formed the body of the box, 75 the lid-fold will close down over the top thereof. The side flaps, *l l*, are bent downwardly at right angles to the fold *d*, the flap *m* on the front edge of the lid is similarly bent, and the ears *n n* on the ends of the flap *m* are folded 80 within the ends of the flaps *l l*, and pasted, riveted, clipped, or otherwise secured to the said flaps. The lid, as will be seen, is now provided with depending lips *l l m*, (on the three free edges,) which are adapted to pass 85 down around the upper edges of the box, and the fourth edge of the lid is hinged or attached to the upper edge of the rear fold, *c*. Thus I have provided a box adapted to contain candies, oysters, &c., or to be used as a millinery 90 or shelf box, which is formed from a single cut, punched, or otherwise-shaped blank, and is provided with an integral lid which fits down over the top of the box and has depending lips to embrace and support the sides of 95 the box. The said box is further provided with strengthening-flaps at the ends to fold over the said ends and interlace, thus protecting and bracing the entire structure and relieving the ordinary fastening devices of a 100 great part of the strain which they must ordinarily bear.

A further and very great advantage of this box is, that there are no loose or unprotected

corners or edges. All corners and edges are carefully concealed or protected except the ends of the outside tongues, g^2 and k^2 , and these are fastened firmly in place. It will be seen that the entire box is held together by the

clips which hold the said tongues down.

Having described my invention, I claim—

1. The box comprising the fold b , flaps h h on the side edges thereof, the folds a and c , and the flaps g and k , having the tongues g^2 g^3 and k^2 k^3 on their outer ends, which are adapted to interlace on the outside of the flaps h h , substantially as and for the purpose specified.
2. The box comprising the bottom fold, b ,

the side folds, a c , the top or lid fold, d , the end flaps, h h , on the fold b , the forked flaps g and k on the folds a and c , respectively, adapted to interlace on the outside of the flaps h h , and the clips O , to fasten the free ends of the forked flaps to the end flaps, h , of the box, substantially as and for the purpose specified.

In testimony that I claim the foregoing as my own I have hereto affixed my signature in presence of two witnesses.

JOHN M. WADDILL.
